Attorney.

UNITED STATES PATENT OFFICE.

JOHN J. RICHTER, OF THIEF RIVER FALLS, MINNESOTA.

METHOD OF MAKING PACKING-RINGS.

1,316,463.

Specification of Letters Patent. Patented Sept. 16, 1919.

Original application filed February 12, 1916, Serial No. 77,954. Divided and this application filed December 6, 1917. Serial No. 205,859.

To all whom it may concern:

Be it known that I, JOHN J. RICHTER, a citizen of the United States, residing at Thief River Falls, in the county of Pennington and State of Minnesota, have invented a new and useful Improvement in Methods of Making Packing-Rings, of which the following is a specification.

This invention relates to the production 10 of packing rings, for use on pistons of engine pumps and similar machines and particularly for pistons of internal combustion engines, wherein the ring will remain tight at all times automatically under working 15 conditions to which rings of this character are generally subject. This application is a division of the subject matter of my companion application Serial Number 77,954, filed on the 12th day of February, 1916, for 20 packing rings, and allowed on the 9th day of November, 1917, the particular feature of novelty claimed in this application relating to the production of a piston ring formed in a plurality of longitudinal parts welded 25 together.

In the accompanying drawing forming part of this specification, Figure 1 is a plan of my invention; Fig. 2 is a plan of a detail and Figs. 3 and 4 are side elevations of de- 30 tails.

In piston rings now in general use there is more or less leakage due to the rings wearing away on their outer faces and the ends separating, thus permitting the fluid or gas 35 under compression to leak through. My invention overcomes this objection by constructing the ring in a plurality of parts welded together, so that the two ends may be made to overlap at any distance desired 40 or not overlap when desired. In this manner a stronger or milder resiliency for wall pressure is produced, so that as the ring wears away in use and opens out, a tight joint will be maintained against the cylinder 45 wall.

In the drawing A indicates the usual body portion of a ring having ends 2 and 3, which are adjacent to each other. Each of these ends is formed with a forwardly projecting 50 side tongue 4 and a laterally projecting shoulder 5 forming a side groove, said tongue being cut away longitudinally on its under or inner edge and said shoulder and groove being formed by a portion of the end of 55 the ring being cut away along the side of

the tongue. The adjacent ends of the ring are similarly constructed each having a side tongue and an adjacent side groove, the tongue in one member entering the groove in the opposite member. The grooves and 60 tongues in the opposite members are of sufficient depth to produce side seating surfaces 6 for the tongues, which will prevent leakage of compressed liquid past the ring when the latter is in use. It will be observed that 65 the ends of the seating surfaces are of enlarged area, so that the ring can expand and contract without opening and leaking.

In producing the ring it is formed in a plurality of longitudinal parts welded together, 70 the drawing indicating for illustration the part 7 welded to the remaining portion to enable efficient machining of inter-locking ends with the overlapping joint as long as desired. The adjacent ends of the interlocking machined parts are scarfed at 8 to receive welding. The plurality of parts machined and welded together then will form the ring, with the overlapping joint as long as desirable. Thus the surfaces can be finished to produce an absolutely leak proof 80 joint. Preferably the ring in normal position has sufficient opening between its ends, so that sufficient expansion of the ring is 85 provided to produce a tight fit in the cylinder with which the ring is employed. While a specific construction of joint has been described, it will be understood that the production of the ring by welding a plurality 90 of longitudinal parts together can be employed with any construction of joint desired wherein the ends overlap or do not overlap. It will further be understood that by welding the parts together as described a much 95 stronger, more efficient and simpler structure is produced than if the ring were constructed by riveting or bolting a plurality of longitudinal parts together. I have found in practice that a successful ring with an interlocking leak proof joint cannot be produced without constructing the ring in a plurality of parts and machining the overlapping ends before said parts are joined together to complete the ring.

In accordance with the patent statutes, I 105 have described the principles of operation of my invention, together with the apparatus which I now consider to represent the best embodiment thereof, but I desire to have it 110 understood that the construction shown is

only illustrative, and that the invention can be carried out by other means and applied to uses other than those above set forth within the scope of the following claims.

5 Having described my invention, what I claim as new and desire to protect by Letters Patent is:

1. The herein described method of making piston rings which consists in taking a metal 10 ring, removing a segment therefrom, taking a segment of the same radius as said ring, forming an overlapped joint between adjacent ends of said ring portion and segment, and rigidly connecting the other ends of said 15 ring portion and segment to complete said ring.

2. The herein described method of making piston rings which consists in taking a metal ring, removing a segment therefrom, taking 20 a segment of substantially the same radius as

said ring, forming an overlapped joint between adjacent ends of said ring portion and segment, scarfing the other ends of said ring portion and segment and flowing molten metal into the joint between the scarfed ends 25 to complete said ring.

3. The herein described method of making one piece piston rings, which consists in taking segments machined to a substantially uniform radius, forming an overlapping joint 30 between adjacent ends of said segments, assembling said segments end to end with their end surfaces abutting and the portions constituting said overlapping joint in juxtaposition and finally rigidly uniting said end 35 surfaces to complete a ring.

In testimony whereof, I have signed my name to this specification.

JOHN J. RICHTER.
